To all whom it may concern:

Be it known that I, Michael Chernow, a citizen of the United States and residing at Brooklyn, in the county of Kings and State of New York, have invented a new, original, and ornamental Design for a Bracelet or the like, of which the following is a specification, reference being had to the accompanying drawing, forming part thereof, and in which

The dominating feature of the bracelet resides in the contour of the initial connecting links having openings through each link forming letters of the alphabet, it being understood that other letters of the alphabet may be used without departing from the spirit of the invention.

I claim:

The ornamental design for a bracelet or the like, substantially as shown and described.

MICHAEL CHERNOW.
